UNITED STATES PATENT OFFICE.

BERT L. VAN ORMAN, OF DETROIT, MICHIGAN, ASSIGNOR TO L. A. YOUNG INDUSTRIES, INC., OF DETROIT, MICHIGAN.

WIRE-FORMING MEANS.

Application filed January 12, 1924. Serial No. 685,787.

To all whom it may concern:

Be it known that I, BERT L. VAN ORMAN, a citizen of the United States, residing at Detroit, county of Wayne, State of Michigan, have invented certain new and useful Improvements in Wire-Forming Means, of which the following is a specification.

This invention relates to improvements in wire working machines.

10 I have illustrated my improvements as I have embodied them in a machine for forming double springs or a spring having independent coils designed for automobile brakes.

15 My improvements are, however, desirable and readily adapted for use in forming springs for other purposes.

The main objects of my invention are:

First, to provide an improved wire working machine which is automatic in its 20 operation except in the matter of feeding and is adapted to form a straight piece of wire into a spring having double coils.

Second, to provide an improved wire 25 working machine of the class described which may be readily adjusted to the work desired.

Third, to provide a machine of the character described which is of large capacity, easy 30 to operate and not likely to get out of repair.

Further objects, and objects pertaining to details and economies of construction and operation will definitely appear from the 35 detailed description to follow.

I accomplish the objects of my invention by the devices and means described in the following specification. The invention is clearly defined and pointed out in the claims.

40 A structure which is a preferred embodiment of my invention is clearly illustrated in the accompanying drawing forming a part of this application, in which:

Fig. I is a plan view of my improved 45 wire coiling or spring forming machine.

Fig. II is a detail vertical section on a line corresponding to line 2—2 of Fig. I.

Fig. III is a detail view, partially in vertical transverse section, on a line corresponding to line 3—3 of Fig. I.

Fig. IV is a detail view mainly in vertical section on a line corresponding to line 4—4 of Fig. I.

Fig. V is a detail view on a line corre-

sponding to line 5—5 of Fig. I showing the 55 relation of the stock as it is introduced to the coilers.

Fig. VI is a view similar to Fig. V showing the coiler heads with the completely 60 coiled spring therein.

Fig. VII is a perspective view of the completed work.

In the drawing the sectional views are taken looking in the direction of the little arrows at the ends of the section lines and 65 similar numerals of reference refer to similar parts throughout the several views.

Referring to the drawing, the table or bed 1 is provided with a central longitudinal slot 2, the purpose of which will appear as 70 the description proceeds. At either side of this slot I mount coiler supports 3, these supports being adjustably secured to the bed by means of the bolts 4 engaging the longitudinal slots 5 so that the supports 75 may be adjusted relative to each other in parallel planes.

Each support carries a coiler spindle 6 having a coiler head 7 thereon, the coiler spindles being provided with feed screws 8 coacting with the feed nuts 9 on the supports so that as the spindles are rotated the heads are moved laterally. Each coiler head is provided with a form core 10 reciprocating axially through the spindle and 85 projecting at the inner end of the coiler head, and with a coiler lug 11, the lug being grooved to retain the wire in engagement therewith.

The spindles are driven to rotate the head 90 and to feed the spindles axially, the driving means illustrated comprising the elongated pinions 12 on the spindles with which the driven gears 13 mesh, the driving gears 14 being connected to the gears 13 to rotate 95 therewith. The driving racks 15 engage these driving gears and are connected to the pitman 16 on the crank gears 17 so that the spindles are driven with a forward and return movement as the racks make one 100 complete stroke.

These gears 17 are driven from a source of power as the pulley 18 is connected through a suitable train of gears and a clutch mechanism indicated generally at 19. 105 This clutch mechanism is controlled by the clutch lever 20 connected by the link 21 to the foot lever 22.

The cam wheel 23 coacting with the roller 24 on the clutch lever (see Fig. II) is designed to hold the clutch out of engagement until the parts have made a complete cycle. As the details of the clutch form no part of this invention they are not further described herein.

The core 10 is reciprocated by means of the levers 25 pivoted at 26, the levers engaging the slots 27 at the outer ends of the cores so that the supports may be adjusted longitudinally without affecting the operating connections. The levers 26 are connected by the links 28 to the arms 29 on the rock-shafts 30, these rock-shafts being also provided with arms 31 which are actuated by the cams 32 on the gear wheels 17, the cams being positioned so that the actuation of the core is properly timed.

With the parts thus arranged the stock indicated at 33 is placed in the machine (see Fig. V) while the coiler heads are at rest. The operator then engages the clutch by pressing the foot lever 22 and the machine is driven through a complete cycle which wraps the wire around the cores, and retracts the cores discharging the wire through the slot 2. This slot permits the ends of the wire to swing as they are wrapped around the cores, the heads 7 being laterally retracted as the winding progresses and the cores being returned to the initial position at the end of the cycle.

I have illustrated my improvements as I have particularly embodied the same in a machine for forming springs having double coils. I have not attempted to illustrate or describe certain modifications or adaptations which I contemplate as I believe the disclosure made will enable those skilled in the art to embody or adapt the same as may be desired.

Having thus described my invention what I claim as new and desire to secure by Letters Patent is:

1. In a wire working machine, the combination of a bed, supports mounted thereon for independent adjustment in parallel planes longitudinally of the bed, a pair of coiler heads provided with eccentrically disposed coiler lugs, spindles therefor carried by said supports and provided with feed screws, feed nuts on said supports coacting with said feed screws whereby the coiler head spindles are moved longitudinally as the coilers are rotated, means for driving said spindles comprising elongated pinions on said spindles, driven gears meshing therewith, driving gears connected to said driven gears, driving racks coacting with said driving gears, means for reciprocating said racks, core members reciprocating axially of said spindles, said core members being slotted at their outer ends, actuating levers for said core members disposed

through their said slots, and means for actuating said levers timed with the actuation of said racks.

2. In a wire working machine, the combination of a bed, supports mounted thereon for independent adjustment in parallel planes longitudinally of the bed, a pair of coiler heads provided with eccentrically disposed coiler lugs, spindles therefor carried by said supports and provided with feed screws, feed nuts on said supports coacting with said feed screws whereby the coiler head spindles are moved longitudinally as the coilers are rotated, means for driving said spindles, core members reciprocating axially of said spindles, said core members being slotted at their outer ends, actuating levers for said core members disposed through their said slots, and means for actuating said levers timed with the actuation of said racks.

3. In a wire working machine, the combination of a pair of coiler heads provided with eccentrically disposed coiler lugs, spindles therefor and provided with feed screws, feed nuts on said supports coacting with said feed screws whereby the coiler head spindles are moved longitudinally as the coilers are rotated, means for driving said spindles comprising elongated pinions on said spindles, driven gears meshing therewith, driving gears connected to said driven gears, driving racks coacting with said driving gears, means for reciprocating said racks, core members reciprocating axially of said spindles, and means for actuating said core members timed with the actuation of said spindles.

4. In a wire working machine, the combination of a pair of coiler heads provided with eccentrically disposed coiler lugs, spindles therefor and provided with feed screws, feed nuts on said supports coacting with said feed screws whereby the coiler head spindles are moved longitudinally as the coilers are rotated, means for driving said spindles, core members reciprocating axially of said spindles, and means for actuating said core members timed with the actuation of said spindles.

5. In a wire working machine, the combination of a pair of oppositely disposed rotary coiler heads, spindles therefor provided with feed screws, core members reciprocating axially of said spindles, said coiler heads being provided with coiler lugs disposed eccentrically relative to said core members, means for driving said spindles whereby the heads are rotated and moved axially, and means for actuating said core members timed with the driving of said spindles whereby the core members are retracted to discharge the work.

6. In a wire working machine, the combination of a pair of oppositely disposed ro-

tary coiler heads arranged in laterally spaced relation and mounted for axial movement and provided with reciprocating axial core members and winding lugs disposed eccentrically relative to said core members, means for simultaneously rotating and axially moving said coiler heads, and means for retracting said core members for discharging the work.

10 7. In a wire working machine, the combination of a pair of oppositely disposed rotary coiler heads arranged in laterally spaced relation, spindles therefor provided with feed screws, core members disposed axially of said spindles, said coiler heads being provided with coiler lugs disposed eccentrically relative to said core members, and means for driving said spindles whereby the heads are rotated and moved axially.

15 8. In a wire working machine, the combination of a pair of oppositely disposed rotary coiler heads arranged in laterally spaced relation and provided with recipro-

cating axial core members and winding lugs disposed eccentrically relative thereto, 25 means for simultaneously rotating said coiler heads, and means for retracting said core members.

9. The combination of a pair of oppositely disposed rotary coiler heads arranged 30 in laterally spaced oppositely facing relation and provided with axial core members and winding lugs disposed eccentrically thereto, means for rotating said coiler heads, and means for retracting said core 35 members.

10. The combination of a pair of oppositely disposed rotary coiler heads arranged in laterally spaced relation and provided with axial core members and wind- 40 ing lugs disposed eccentrically thereto, and means for simultaneously rotating said coiler heads.

In witness whereof, I have hereunto set my hand.

BERT L. VAN ORMAN.
